BREAST MOLDING FOUNDATION GARMENT

Louis Joseph Adjutor Amyot, Quebec, Quebec,
Canada

Application November 30, 1940, Serial No. 368,052

3 Claims. (Cl. 2—42)

This invention relates to breast molding foundation garments and it comprises a garment in which the breast pockets are designed to distribute the pull of the shoulder straps uniformly over the width of the pockets in such manner that the breasts are given an exceptionally high, well separated and rounded appearance and are adequately supported from beneath.

An important feature of the invention consists in the provision of a garment in which the shoulder straps are attached to the apices of triangular extensions provided at the upper edges of the pockets, each of said extensions being provided with a multiplicity of closely spaced lines of stitching which diverge downwardly from the apex thereof and serve as strain distributing members by which the upward pull of the attached shoulder strap is uniformly distributed over the entire width of the pocket.

Another feature resides in the provision of a garment of the character described in which the triangular extension of each pocket is of two ply construction, one ply constituting an integral extension of the upper part of the breast pocket and being cut on the bias and the other ply being cut the way of the weave and joined to the first mentioned ply by the aforesaid lines of stitching.

Another feature is to provide a garment in which the aforesaid lines of stitching are arranged to cause the upper portions of the pockets to cling closely to the upper portions of the breast and to exert substantially uniformly distributed molding pressure thereagainst.

A further feature of this invention resides in the provision of a garment in which petal shaped reinforcing or stiffening members are incorporated in the lower sections of the breast pockets in a novel manner to give an uplifting support to the breasts.

Other features and advantages of this invention will become evident from the following detailed description taken in connection with the accompanying drawing, in which:

Figure 1 is a perspective view of this invention as it appears about the wearer.

Figure 2 is a view in rear elevation disclosing the inner surface of the front portion of the garment.

Figure 3 is a side elevational view of the garment as it appears about the wearer.

Figure 4 is a section along the line 4—4 of Figure 1.

Referring more particularly to the drawing, 5 designates a breast supporting garment compris-

ing breast pockets 6, side sections 7 and a front waist band 8. The breast pockets are divided into upper and lower sections 6a and 6b joined together by a line of faggotting 9 which extends across the centre of the breasts. The inner vertical edge of each section 6a is stitched to the adjacent edge of a gusset 10 which is located therebetween. The lower edge of each section 6b is stitched to the upper edge of the waist band 8. The outer vertical edges of the sections 6a and the band 8 are conjointly stitched to the adjacent vertical edges of the side sections 7. The side sections 7 are provided with suitable fastening means adjacent their free vertical edges adapted to secure the garment about the body of the wearer. The garment is also provided with the usual shoulder straps 11 which are joined to the upper edges of the breast pockets 6 and the side sections 7.

The upper section 6a is cut on the bias to provide a preformed mold for the upper portion of the breast, the upper edges converging from the vertical side edges to form a triangular extension 14 having its apex 12 substantially above the nipple of the breast. The triangular extension 14 is of two ply construction, one ply 14a constituting an integral extension of the upper part of the breast pocket section 6a and the other ply 14b being cut the way of the weave and joined to the first mentioned ply by means of a multiplicity of closely spaced lines of stitching 15 which diverge downwardly from the apex thereof and serve as strain distributing members by which the upward pull of the shoulder strap 11, which is attached to the apex 12, is uniformly distributed over the entire width of the pocket.

The base of the ply 14b is concavely curved with its extremities tapering toward the vertical side edges of the section 6a to conform with the upper curved line of the molded breast. The marginal edges of the reinforcing ply 14b are stitched to the ply 14a by lines of stitching 16. The shoulder strap 11, which has one end secured to the apices of the triangular extension ply 14 and its reinforcing ply 14b, exerts an even pull through the downwardly diverging lines of stitching 15 and 16 on the entire width of the extension 14. If not reinforced the bias ply 14a would naturally form elongated pleats between the lines of stitching. The reinforcing ply 14b on the other hand, which is cut the way of the weave, has a greater tendency to flatten itself out, thus eliminating the creasing in the upper section of the breast pocket. The outer edge of the ply 14b would be receiving its tension on the bias line but this is offset by the fact that the bias ply 14a

would, at this point, be tensioned against the way of the weave. As the pull tends to flatten the extension 14 the concavely curved base of the ply 14b exerts an inward pull at that point which draws it into the hollow formed between the chest and the upper portion of the molded breast, thus fitting the entire upper section 6a snugly about the upper portion of the molded breast.

The upper portion of the breast pockets being built up in the above described manner also prevents the shoulder straps 11 from slipping off the shoulder, since the tension is evenly distributed and will not therefore allow sagging of the outer side of the pocket section 6a.

The lower section 6b of the pocket 6 is cut to conform with the molded curve of the lower half of the breast, the lower edge being convexly curved and stitched to a concavely curved edge portion of the waist band 8. Petal shaped reinforcing or stiffening members 17, preferably made of a "Cordtex" material described in Canadian Patent No. 361,754, are provided in the lower portion of section 6b to give an uplifting support to the breast. The members 17 are stitched to the under side of the section 6b with their lower ends tangentially converging adjacent the bottom edge of said section 6b, and extend upwardly in an outward or radial flaring direction. The lower portion of the side edge of each member 17 is fitted to the corresponding edge of the adjacent member to conjointly provide a continuous wide reinforcing area while the upper portion of the side edge diverges from the corresponding edge of said adjacent member. The two centre members have their upper portions on either sides of the breast so that the portion of the breast directly below the nipple is supported in the crotch formed thereby.

A lining 18 of French net or other suitable material is stitched to the inner surface of the breast pocket section 6b to afford protection from possible chafing of the breast by the members 17.

The waist band 8 is made of a one way lateral stretch lastex material which is shaped at its

upper edge to define a pair of semi-circular cut away portions adapted to conform with the natural curve of the base of the breast, and an upwardly projecting portion therebetween which is stitched to the lower end of the gusset 19 for the purpose of dividing the breast pockets.

Having thus described my invention, what I claim is:

1. A breast molding garment provided with breast molding pockets, a two-ply triangular extension projecting upwardly from the upper half of each pocket, the said upper half of each pocket and one ply of said extension being made in one piece of bias cut fabric material, the remaining 10 ply of each triangular extension being made of fabric material which is cut on the weave and being stitched along its marginal edges to the companion bias cut ply, the two plies of each extension being also secured together by vertically 15 extending lines of strain distributing stitches which extend downwardly, in diverging relation to each other, from the apex of said extension to the lower edge of the non-bias cut ply of said extension, and a shoulder strap secured to each extension at the apices of the component plies of 20 said extension.

2. A garment as set forth in claim 1 in which the lower half section of each breast pocket is provided with reinforcing elements extending upwardly from the lower edge of said section in 25 diverging relation to each other.

3. A breast molding garment comprising breast pocket sections, the upper half of each breast pocket section being cut on the bias and extended 30 to provide an upwardly directed triangular extension, a reinforcing ply stitched to said triangular extension, said reinforcing ply being made of fabric cut on the weave and being joined to said extension by vertical lines of strain distributing stitching extending downwardly, in diverging relation to each other, from the apex of 35 said extension.

LOUIS JOSEPH ADJUTOR AMYOT.
